HEAT EXCHANGING ELEMENT AND PROCESS
OF MAKING THE SAMEAlfred J. Berg, Portsmouth, N. H., and John O.
Huse, United States Navy

Application February 14, 1936, Serial No. 63,894

8 Claims. (Cl. 29—157.3)

(Granted under the act of March 3, 1883, as
amended April 30, 1928; 370 O. G. 757)

Our invention relates primarily to a new and useful heat or cold exchanging element and process of making the same, although the same may be otherwise usefully employed.

5 In the whole of the prior art in order to associate at least one rib with the heat exchanger element which may be hollow and have an arched surface, a flat strip of metal has been bent edgewise about such surface and suitably secured thereto. Some in such art have edgewise formed or pre-coiled the flat strip into the desired shape to apply to the surface of the member. These operations are difficult and tedious operations requiring time and substantial 10 expense as well as involve substantial wear upon the forming apparatus employed requiring its frequent and expensive replacement. Such forming stresses, where the strip is edgewise bent or formed to the desired shape directly upon the heat or cold exchanging element, have required that the wall of such element be heavier and more expensive than otherwise required in order to resist such forming pressure without deforming the wall of the heat exchanger element. 15 Furthermore, the working temperature of such edgewise formation of the flat strip of metal to make the fin for the heat exchanger element has been in many cases so intense as to destroy the normal cold rolled or cold worked characteristics 20 of the metal of the strip, thus reducing its rigidity, resistance to deformation, as well as lowering its heat or cold exchanging capacity.

A further inherent difficulty in the edgewise formation of a flat strip of metal about an arched surface of a tube or cylinder is and always has been that even with ductile metals the width of such formed strip cannot exceed about one-half the diameter of the circle about the whole or a portion of which the strip may be bent edgewise. 25 Wider strips have been so bent edgewise by one or more operations preforming the strip by edgewise bending to the desired or something near the desired diameter. Each such pre-bending or coiling is but progressive stages with intervening annealing or normalizing the metal of the bent strip. This involves substantial time and production costs. And even these auxiliary operations have their limits as to the height of bent rib producible thereby.

30 We, with legions of others, have for many years heretofore been more or less extensive witnesses to lathe and other machine tools cutting a shaving, whose thickness may vary with the requirements of each particular job, and which shaving is frequently of great length. Heretofore, in shop

practice the length of such shavings became a menace to the operators of the machinery and others due to their gyrations about the floor and elsewhere. These gyrations have occasioned injury to the persons and property and are liable to occasion others. To reduce such menace such shavings have been cut in small pieces by the machine operator into short lengths as the shavings come from the machine and placed in the shavings-scrap receptacle. When the cutting tool cuts upon a cylindrical surface the shavings are formed into a thin cylindrical helical flat coil. When a side cutting tool cuts the required depth commencing at an end of a cylindrical hollow bar the shaving is helical, thin and of similar side surface dimensions to the end of the bar from which they were severed. In either case, such chips or shavings have been in steel as thin as .00014 of an inch of substantial width and hundreds of feet long without breaking. Other shavings have been as wide as 4 inches, about .001 of an inch thick and many hundreds of feet long without breaking. Such shavings or chips have been heretofore scrap and of no utility except for re-melting.

35 One of the very substantial inventive concepts of our present invention is our concept that all of the heretofore indicated troubles and limitations arising from forming a flat strip edgewise to the desired curvature and/or helix are overcome by cutting a shaving of metal of the desired thickness, curvature, form and width, and applying such cut shaving as the rib or fin of the heat exchanger element. In this case the center of the shaving is provided with an opening conforming to the exterior surface of the heat or cold exchanging member. Such opening may be formed in the center of the end of the bar of metal from which such shaving is cut helically by a broad thin side cutting tool which may be of the usual construction. Such helical shaving or a portion of an end thereof is slipped over the heat exchanging element. Such shaving being of uniform width and thickness with thickness and consistency of metal throughout its length will, upon being stretched, assume substantially uniform spaces between the helices, such spacing being proportionate to and controllable by such stretching stress. When the helical shaving is of the desired spacing between the helices the shaving may be secured at or near opposite ends of the tube or heat or cold exchanging member, such securement being by a drop of solder or otherwise as may be convenient or desirable. Thereupon, the thus secured shav- 40 45 50 55

ing is severed from its unsecured remainder. By this process of employing a shaving helically cut from the end of a bar of the desired metal and having the desired end, external and internal, dimensions further revolutionize the making of finned heat or cold exchanging elements or tubes in this—that heretofore the element or tube had to be placed in a lathe or like tool and rotated at substantial velocity while the strip of metal 10 was being bent edgewise about or otherwise applied thereto, whereas, in accordance with our present invention the application of the fin or rib structure to the element or tube simplifies itself into a mere bench operation requiring no tools except those that may be necessary to solder or otherwise secure at desired intervals the cut or turned to final form of our fin or rib structure to the element or tube. Thus, it becomes apparent that our method may be practiced by hand even upon a commercial basis.

In such practice, however, the size and shape of the central opening in the chip or shaving must substantially conform to the contour of the heat or cold exchanging element or tube. Where the size and shape of the central opening in the helical chip or shaving is larger than the contour of the heat or cold exchanging element or tube, the shaving in such case is rolled or otherwise subjected to inward pressure progressively applied about its exterior edge to produce a close physical contact between the inner edge of each helices of the helically coiled chip or shaving and exterior surface of the heat or cold exchanging element or tube to produce an efficient heat or cold exchanging contact.

In the drawings illustrating our invention Figure 1 is an end elevation view of a bar of metal, which is cylindrical in the instance shown associated with a tool for cutting the requisite thickness of shaving therefrom;

Fig. 2 is a top plan view of the parts shown in Fig. 1;

Fig. 3 is a top plan view of a heat or cold exchanging element or tube provided with a helical rib or fin cut from the bar indicated in Figs. 1 and 2;

Fig. 4 is an end elevation view of the heat or cold exchanging element or tube provided with the cylindrical helically coiled rib or fin aforesaid and a roller for insuring the firm contact of the inner edge of the rib or fin with the exterior surface of the heat or cold exchanging element or tube as well as for securing the same together as hereinafter explained;

Fig. 5 is a sectional elevation view on lines 555—5 of Fig. 4;

Fig. 6 is a central, vertical, sectional view of a portion of the roller shown in Figs. 4 and 5;

Fig. 7 is a top plan view of a portion of the periphery of the roller shown in Fig. 6;

Fig. 8 is a central, vertical, sectional view of a portion of a heat or cold exchanging element or tube and the helical ribs formed of a specially cut shaving having an internal shoulder; and

Fig. 9 is a view of the cutting tool for cutting the shaving indicated in Fig. 8.

In the drawings in which like characters of reference indicate the same parts, 10 represents a bar of the metal desired to form the heat or cold exchanging rib or fin 11. Said bar 10 is provided with a central opening 12 which may be of such size and shape that the central opening through the shaving forming the heat or cold exchanging rib 11 if such is to conform to the exterior surface of the tube or other shaped member

13, which may be hollow. The outer circumference of the bar of metal 10 may be of the external shape desired for the heat or cold exchanging rib 11.

The bar of metal 10 may be revolvably mounted in a lathe or other machine tool, not shown, having a relatively thin side cutting tool 14, Fig. 1, 2, whose point extends into the central opening 12 in order to insure the complete severance of the shaving 11 from the bar 10. As the bar 10 is rotated in the lathe or like machine tool, the cutter 14 is moved longitudinally into the bar 10 at such a rate as will afford the requisite thickness to each of the helical cut portions of the shaving, helices 11.

The bar 10 may be either forged, cold worked, or cast metal of the kind adapted for and desired to be used to form the heat or cold exchanging rib 11 of the heat or cold exchanging element 13. This metal may be either ferrous or non-ferrous, but we prefer to employ the non-ferrous metal for its greater ductility and freedom from substantial corrosion. Very satisfactory results have been obtained by us from non-ferrous metal, particularly copper and aluminum, and alloys in which such metal is a substantial content. Such results have been obtained with very thin fins 11 which may extend any desired height from the member 13 according to the exterior dimension of the bar 11 from which they were cut. Satisfactory results have also been obtained where the bar 10 was of ferrous metal although the metal of the rib 11 was thicker in order to withstand protracted corrosion.

We have further found that the cutter 14 in severing the shaving 11 from bar 10 cold works the opposite lateral surfaces of the shaving 11. This cold working distorts the grain of the metal of the shaving and increases its surface density. Such distortion and increased surface density increases the ductile strength and rigidity of the shaving, permits a thinner shaving to be made of high resistance to deformation, substantially increases the height that the rib or fin 11 may project beyond the surface of the heat or cold exchanging member 13, increases the number of such ribs that may project from each unit of length of the heat or cold exchanging member 13, increases the thermo-conductivity of the heat or cold exchanging element 13 provided with such ribs 11, and reduces the weight, cost and size of the required heat or cold exchanging unit comprising the desired plurality of the elements 13 provided with the ribs 11.

After a desired length of the helical shaving 11 has been cut from the bar 10, such shaving 11 may be severed from such bar and a portion thereof applied to the element 13. In such application one end of the shaving 11 is suitably secured at its inner edge to the element 13. This securing in Fig. 3 is designated as 15 and may represent solder or any other convenient securing. This securing is initially at the inner edge of one end of shaving 11 to the desired point upon element 13. The adjacent portion of shaving 11 may then be slightly stretched by hand in order to obtain the requisite distance between each of the helices of the helical chip 11. Inasmuch as the chip 11 is uniformly dimensioned throughout its extent and of the same homogeneous metal, this spacing apart of the different helices of the helical shape 11 will be uniform. This chip 11 may then like-wise be secured at least at the most distant point on element 13 from its initial securing and the residue of chip 11 severed. Our

method of making the heat or cold exchanging element 13 with the chip 11 may thus be practiced by hand as a bench operation disassociated from and without requiring any expensive machine or 5 labor sufficiently experienced to operate such machinery. Such hand production may also be conducted upon an advantageous commercial basis. In such hand practice of our method the inner edges of each of the portions of chip 11 will 10 be in firm thermal-contact with the exterior surface of the element 13 when the central opening 12 in bar 10 is of the appropriate size and shape. When such opening 12 is not of such appropriate size and shape, then each progressive portion of 15 the shaving 11 may be passed through the slit 16 in roller 17 having a central bearing 18 adapted to receive a suitable spindle, not shown. The wall 19 at the bottom of slot 16 is adapted to engage the peripheral edge of the shaving 11, while the 20 sides of slot 16 approximately engage the lateral surface of the shaving 11. The roller 17 may be mounted to move in the desired path about or along the element 13. This path may be in a straight line or in a helix, as may be desired. 25 When such straight line movement comprehends the formation of the shaving 11 in a ring about the element 13, the shaving may be severed and its adjacent substantially abutting edges left free or secured together. 30 The movement of roller 17 along the outer edge of shaving 11 presses the shaving 11 inward and sets the metal content of the shaving 11 in firm thermal contact with the outer surface of the element 13. This contact is sufficient in many 35 cases to afford the requisite securing of the shaving 11 to the element 13. In any instance where the same is not a sufficient securing, solder may be employed or other convenient secures may be used. One of such other secures, which is conveniently applied simultaneously with the functioning of the roller 17, is to provide a plurality of very small bevelled projections 20 on the peripheral edge of roller 17 on opposite sides of the slot 16. Such projections 40 20 may be staggered relative to each other on opposite sides of the slot 16. These projections 20 form slight indentations in the exterior surface of the element 13 close to the opposite sides of the inner edge of shaving 11. Such slight indentations raise creasing projections 21, each of which comprise metal of the element 13. At least one surface of each of said slight projections 21 firmly engage opposite sides of the inner edge of the shaving 11. Such projections 21 being staggered relative to each other upon opposite sides of 45 the shaving 11 tend to inwardly stress the portion of shaving 11 extending between each pair of projections 21. Such stress may extend to the degree of providing a slight kink in such portion of the shaving between each pair of projections 21 where the shaving 11 is thin. Such stressing of the metal of shaving 11 between each pair of projections 21 affords a simple inexpensive and highly efficient securing of the shaving 50 11 progressively throughout its extent along or about the element 13.

In heat exchanger, or other uses, where thin shavings 11a are desired to be employed analogous to the shaving 11 but with a contact with the 55 surface of element 13 comprising an area of greater width than the normal thinness of the shaving 11a, the shaving 11a is cut with a curved inner edge 11b whose inner surface contacts with the outer surface of element 13 throughout a 60 substantially wider area than the normal thinness 75

of the shaving 11a. This shaving 11a with the curved inner portion 11b is cut with a very thin cutter 14a whose curved point 14b extends into the opening 12 in the bar 10 in order to insure the complete severance of each portion of 5 the chip 11a from the bar 10 from which it was made. Such bent portion 11b tends to exert not only a greater area of frictional contact with the surface of the element 13, but it also tends to engage the surface of element 13 with a spring 10 stress due to the curved portion 11b. The inner edge 11b of shaving 11a, in uses where such frictional and spring engagements may be deemed insufficient securing to the element 13, additional 15 securing may be afforded in either of the ways hereinbefore stated for the chip 11.

It will be apparent, at least to those skilled in this art, that our invention provides a simple, durable, inexpensive and highly efficient heat and cold exchanging article that may also be advantageously employed in other uses. 20

While we have shown the rib as being sheared or cut or severed from a round bar of metal, we do not thereby desire to be misunderstood as limiting our invention to the shape of the bar from which the rib is cut, as the bar may be of other desired shapes such as square, hexagonal, octagonal, oblong, elliptical, and any other desired shape, with the central opening in the bar from which the fin is made, such opening being required only when the rib is to surround an element; likewise the same grain distortion, cold working and other properties afforded by our invention to the rib, may be enjoyed even by a straight rib whose lateral surfaces have been 30 sheared or cut from a block of metal of the requisite dimensions. 35

The Government of the United States may make and use and have made for its use for governmental purposes the foregoing invention without the payment of any royalties thereon or therefor. 40

Having now so fully described our invention that others skilled in the art may therefrom make and use the same, what we claim is:— 45

1. The method of making a helical heat exchange fin comprising progressively and substantially uniformly cutting a bar of high heat conductivity metal continuously at its end and in the direction of its length to directly form by the 50 cutting operation a helical heat exchange fin having a substantially uniform thickness throughout and a height equal to many times its thickness, the said fin being adapted to be secured to a heat exchange element. 55

2. The method of making a helical heat exchange fin comprising progressively and substantially uniformly cutting a longitudinally apertured bar of high heat conductively metal continuously at its end and in the direction of 60 its length to directly form by the cutting operation an apertured helical heat exchange fin having a substantially uniform thickness throughout and a height equal to many times its thickness, the said fin being adapted to be 65 secured to a heat exchange element.

3. The method of making a heat exchange device including a heat exchange element provided with a helical heat exchange fin secured thereto, comprising progressively cutting a bar 70 of high heat conductivity metal continuously at its end and in the direction of its length to directly form by the cutting operation a helical heat exchange fin, and securing the said fin so formed to a heat exchange element. 75

4. The method of making a heat exchange device including a heat exchange element provided with a helical heat exchange fin secured thereto, comprising progressively and substantially uniformly cutting a longitudinally apertured bar of high heat conductivity metal continuously at its end and in the direction of its length to directly form by the cutting operation an apertured helical heat exchange fin having a substantially uniform thickness throughout and a height equal to many times its thickness, positioning the said fin so formed about a heat exchange element and securing the fin thereto.
5. A cut helical heat exchange fin of high heat conductivity metal adapted to be secured to a heat exchange element, said fin having a substantially uniform thickness throughout and a height equal to many times its thickness, the entire lateral surfaces of said fin being formed by a cutting operation and cold worked by the cutting.
6. A heat exchange device comprising in combination a heat exchange element and a cut apertured helical fin of high heat conductivity positioned about and secured to said heat exchange element, said fin having a substantially uniform thickness throughout and a height equal to many times its thickness, the entire lateral surfaces of said fin being formed by a cutting operation and cold worked by the cutting.
7. The method of making a heat exchange device including a heat exchange element provided with a helical heat exchange fin secured thereto, comprising progressively and substantially uniformly cutting a longitudinally apertured bar of high heat conductivity metal of an outer diameter greater than twice its inner diameter continuously at its end and in the direction of its length to directly form by the cutting operation an apertured helical heat exchange fin having a substantially uniform thickness throughout and a height greater than one-half the diameter of the heat exchange element to which it is to be secured, positioning the said fin so formed about a heat exchange element having an outer diameter substantially equal to the inner diameter of the aforesaid fin and securing the fin at its inner periphery thereto.
8. A heat exchange device comprising in combination a heat exchange element and a cut apertured helical fin of high heat conductivity positioned about and secured to said heat exchange element, said fin having a substantially uniform thickness throughout and a height greater than one-half the diameter of the aforesaid element, the entire lateral surfaces of said fin being formed by a cutting operation and cold worked by the cutting.
